UNITED STATES PATENT OFFICE

136,052

DESIGN FOR A TABLECLOTH OR SIMILAR ARTICLE

Morris Setton, Brooklyn, N. Y.

Application April 28, 1943, Serial No. 110,066

Term of patent 3½ years

To all whom it may concern:

Be it known that I, Morris Setton, a citizen of the United States, residing at Brooklyn, county of Kings, city and State of New York, have invented a new, original, and ornamental Design for a Tablecloth or Similar Article, of which the following is a specification, reference being had to the accompanying drawing, forming part thereof, wherein the figure is a plan view of a tablecloth or similar article, showing my new design.

I claim:

The ornamental design for a tablecloth or similar article, substantially as shown.

MORRIS SETTON.
